Primary Examiner — T. Chase Nelson*Assistant Examiner* — Kathleen M Sims(74) *Attorney, Agent, or Firm* — QuickPatents; Kevin Prince(57) **CLAIM**

I claim the ornamental design for a pop-up batting cage, as shown and described.

DESCRIPTION

FIG. 1 is a perspective view of a pop-up batting cage, showing my new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof;

FIG. 5 is a bottom plan view thereof;

FIG. 6 is a cross-sectional view thereof; and,

FIG. 7 is a bottom perspective view thereof.

The broken line showing of tie ropes in FIG. 1 is included for the purpose of showing environmental matter that forms no part of the claimed design.
